UNITED STATES PATENT OFFICE.

CONRAD KLEIN, OF FRANKLIN SQUARE, NEW YORK, ASSIGNOR TO ENGLANDER SPRING BED COMPANY, OF BROOKLYN, NEW YORK, A CORPORATION OF NEW YORK.

CRIB.

Application filed June 24, 1924. Serial No. 721,975.

To all whom it may concern:

Be it known that I, CONRAD KLEIN, a citizen of the United States, residing at Franklin Square, Long Island, in the county of 5 Nassau and State of New York, have invented certain new and useful Improvements in Cribs, of which the following is a specification.

This invention relates to bed structures, 10 and more particularly that type known as cribs, an object of the invention being to provide an improved crib having enclosing sides extending above the crib bottom or mattress section, wherein one or both of the 15 sides are constructed in the form of a suitable gate adapted to be readily lowered to permit access to the interior of the crib and also to be locked in elevated position to form an effective enclosure.

20 A further object of this invention is to provide an improved crib having a shiftable gate enclosure provided with improved means for releasing the same to permit the lowering and raising of the gate, wherein 25 the construction is simplified, easily operated, serviceable in use, and relatively inexpensive to manufacture.

30 A further object of this invention is to provide an improved crib having a gravity shiftable gate enclosure guided upon the bed framework for vertical slidable movement, and wherein improved mechanism is provided for releasably locking the gate enclosure in elevated position, and also having improved means adapted to be operated by the foot for controlling the locking mechanism.

35 Other objects of this invention will appear in the following description and appended claims, reference being had to the accompanying drawings forming a part of this specification wherein like reference characters indicate corresponding parts in the several views and wherein Fig. 1 is a 40 side view, partly broken away illustrating an embodiment of my invention; Fig. 2 is an enlarged fragmentary sectional view taken substantially on line 2-2 of Fig. 1, illustrating the locking mechanism in locking position; Fig. 3 is a similar view illustrating the locking mechanism when released; Fig. 4 is a detail view illustrating a 45 part of the locking mechanism at one end of

the bed; Fig. 5 is a detail view illustrating a part of the locking mechanism at the opposite end of the bed and Fig. 6 is a sectional view taken substantially on line 6-6 of Fig. 3 in the direction of the arrows.

55 Before explaining in detail the present improvement and mode of operation thereof, I desire to have it understood that the invention is not limited to the details of construction and arrangement of parts which are illustrated in the accompanying drawings, since the invention is capable of other 60 embodiments, and that the phraseology which I employ is for the purpose of description and not of limitation.

65 The present improved crib structure comprises in general a pair of upright end frames detachably connected together by a suitable spring mattress section. The crib is provided with side frames adapted in normal position to extend a substantial distance above the mattress section and form 70 an enclosure. Where desired one of the side frames may be fixed to the framework and the other side frame constructed to be lowered and elevated, or where desired both side frames may be similarly constructed to 75 permit either one to be raised or lowered.

80 In the present instance, it is deemed sufficient to illustrate one side only of the crib and the mechanism for permitting one of the side frames to be raised or lowered, 85 since if desired a similar construction may be utilized for the opposite side of the crib. In this instance, the side frame is constructed in the form of a gate which is guided upon the end frames for sliding movement 90 in a vertical plane. Mechanism is provided for releasably locking the gate in elevated position and a single foot control is provided for operating the locking means, the improved construction being such that it is 95 merely necessary to press down with the foot upon the foot control or pedal release and allow the gate to descend by gravity to its lowermost position, spring bumpers being provided for absorbing the shock of 100 descent of the gate.

105 Referring to the drawings wherein a present preferred form of the invention is illustrated, it will be seen that the crib structure comprises a pair of upright end frames 9 and 10 having supporting legs resting upon

the floor. Detachably connected to these end frames is a suitable spring mattress section comprising end frames 11 and 12 connected together by a spring fabric 50. 5 In the present instance, the frame 12 of the spring mattress section is in the form of a U-shaped member comprising a horizontal transverse bar 12^a bent at the opposite ends thereof to form depending members which 10 are detachably connected to the end frame 10. In like manner, the end frame 11 at the opposite end of the bed is U-shaped in form and comprises a horizontal transverse bar 11^a bent to form depending ends detachably 15 connected to the member 9. The end frames 11 and 12 of the mattress section are suitably connected together by side bars 13. Secured to each end member 9 and 10 adjacent to the top and bottom thereof are 20 a pair of brackets 14 and 15, and secured to each pair of brackets 14 and 15 is a vertical guide rod 16. Each guide rod 16 at its lower end is threaded to screw into a tapped hole in bracket 15, the upper end of each rod 16 25 being threaded and extending freely through bracket 14, this rod being held in place by a knob 14^a screwed on to the upper end thereof. By unscrewing knob 14^a and rod 16 from bracket 15 the rod may be readily 30 removed from the brackets to permit the removal of gate 17, so that the crib may be readily used if desired without the gate, or may be readily knocked down or assembled. The vertical guide rods or members 16 at opposite ends of the crib form 35 guides for a side frame or gate enclosure 17. The gate 17 comprises a pair of horizontal bars 18 and 19 extending substantially the length of the crib and are connected together 40 by vertical rods or bars 20 thereby forming a rigid framework. The upper bar or rod 18 of the gate terminates at its opposite free ends in guide members 18^a, each provided 45 with a hole or aperture freely embracing a guide rod 16. In like manner the lower bar or rod 19 of the gate frame terminates at its opposite free ends in guide members 19^a provided with holes for the reception of the 50 guide rods 16. From this construction it will be seen that the gate 17 is supported upon the vertical guide rods 16 for vertical 55 shiftable movement. Locking mechanism is provided for releasably locking the gate in elevated position. This mechanism comprises a shiftable rod 21 supported at one end of the gate, this rod extending freely through an aperture in the bracket 15 and being 60 bent to provide a horizontal projecting portion 22 terminating in a pedal 23 located conveniently adjacent to one of the legs of the end member 10 of the crib.

The upper end 24 of the rod 21 extends freely through a bracket 25 secured to the end member 10 and a coil spring 27 is interposed between the bracket 25 and the

headed end 26 of the rod 21. Below the bracket 25, the rod 21 is offset or bent inwardly to provide a horizontally extending portion 28 which is housed within the bifurcated end 29 of a two-armed locking member or latch 30. This locking member 30 comprises a horizontal arm terminating in the bifurcated portion 29 and also a vertically extending arm 31 provided with a projecting hooked end or catch 32 adapted to be shifted into and out of position beneath the bar 19 of the gate 17 as clearly shown in Figs. 2 and 3.

Secured at its end to the locking member 30 at a point adjacent to the intersection of arms 29 and 31 of the locking member is a rod or rock shaft 33 which is rotatably supported at one end of the bed by a bracket 34 secured to the upper face of the transverse bar 12^a. The rod 33 thus extends at one end through a hole in the vertical part of the bracket 34 and is adapted to turn therein, and this rod extends the length of the bed along one edge of the spring fabric 50, and at its opposite end is supported for rotatable movement by a corresponding bracket 34^a secured to the transverse bar 11^a of the end frame 11. A locking device 30^a is secured to the rod at the outer face of the bracket 34^a and comprises a vertical arm having a projecting hook or catch 32^a adapted to extend beneath the bar 19 of the gate.

From the foregoing construction it will be seen that the locking mechanism proper for maintaining the gate in elevated position comprises a locking member or device 30 at one end of the crib, shown as the right hand end in Fig. 1, and a locking member or device 30^a at the opposite end of the crib. These locking members are connected together by the lengthwise extending rod or rock shaft 33 supported at opposite ends of the spring mattress section and adapted to be rotated or rocked for simultaneously shifting the parts 32 and 32^a of the locking members into and out of position beneath the bar 19 of the gate when in elevated position. A single mechanism is provided for shifting both locking devices, which is accomplished by means of the rod 21 connected to the arm 29 of the locking member 30 so that upon pressing down upon the foot pedal 23 the rod 33 will be partially rotated or rocked thereby swinging the locking members 30 and 30^a. It will be seen that upon pressing down the pedal 23 to lower the rod 21 the spring 27 will be compressed, so that upon releasing the pedal 23 this spring will operate to return the rod 21 to normal position thereby tending at all times to force the locking member 30 into locking position as shown in Fig. 2.

When the gate 17 is in elevated position

as shown in full lines in Fig. 1, pressure with the foot upon the pedal 23 will shift the rod 21 downwardly thereby swinging the arm 29 of locking member 30 downwardly, partially rotating the rod 33 and causing the parts 32 and 32^a of the locking device to be swung rearwardly out of position beneath the bar 19 of the gate. Thereupon the gate will automatically descend by gravity upon the guide rods 16 to the position shown in dotted lines in Fig. 1. The brackets 15, to which the lower ends of the guide rods 16 are secured, act as stops for limiting the downward movement of the gate, and the shock of fall of the gate 17 is cushioned by means of coiled springs 35 at the lower ends of the guide rods 16. These springs absorb any shock or noise incident to the lowering of the gate and are important in thereby permitting the gate to fall entirely by gravity without any intervention from the user. From its lowermost position shown in dotted lines in Fig. 1, the gate is raised by hand and by a simple pressure upon the pedal 23, the locking ends 32 and 32^a of the latches will be swung rearwardly out of the path of the bar 19 so as to permit the gate 17 to be raised sufficiently to permit the bar 19 to reach the position shown in full lines in Fig. 1 at which point the pedal 23 will be released and the action of spring 27 will swing the locking devices 30 and 30^a into position to permit the locking ends thereof to move into position beneath the bar 19 and support the gate.

As hereinbefore stated, the rod 21 extends freely through brackets 15 and 25, and the rod may be readily disconnected from the locking member 30 merely by grasping the pedal 23 and turning or rotating the rod to swing offset 28 out of the crotch 29 in the locking member. Thus the gate 17 and guides 16 may be readily removed, and after disconnecting rod 21 from the locking member 30, as above described, the mattress section may be easily detached from the ends 9 and 10.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. In a crib, the combination of upright supporting members, a mattress section connected thereto, a vertically slidable gate guided on said supporting members, said gate comprising upper and lower horizontally extending bars connected together,

rotatable shaft, a pair of locking members secured to said shaft and adapted to shift into and out of engagement with said gate for releasably locking the same, and means for rotating said shaft to swing said locking members about the axis of the shaft.

2. In a crib, the combination of upright supporting members, a mattress section connected thereto, a vertically slidable gate guided on said supporting members, said gate comprising upper and lower horizontally extending bars connected together, a rotatable shaft, a pair of locking members secured to said shaft and adapted to shift into and out of engagement with said gate for releasably locking the same, and means connected to a locking member for rotating said shaft to swing said locking members about the axis of the shaft.

3. In a crib, the combination of upright supporting members, a mattress section connected thereto, a vertically slidable gate guided on said supporting members, said gate comprising upper and lower horizontally extending bars connected together, a pair of locking members shiftable into and out of engagement with said lower bar for releasably locking said gate, a rock shaft connecting said locking members together, means for rotatably supporting said shaft and means for rocking said shaft.

4. In a crib, the combination of a pair of upright supporting members having legs resting on the floor, a mattress section extending therebetween, a vertically slidable gate guided by said supporting members, a shiftable locking member for releasably locking the gate in position, and an operating member therefor, one of said members being carried by a supporting member and the other by the mattress section.

5. In a crib, the combination of a pair of upright supporting members having legs resting on the floor, a mattress section extending therebetween, a vertically slidable gate guided by said supporting members, a shiftable locking member carried by the mattress section for releasably locking the gate in position, and an operating member carried by a supporting member and releasably connected to said locking member for operating the same.

6. In a crib, the combination of a pair of upright supporting members having legs resting on the floor, a mattress section extending therebetween, a vertically slidable gate guided by said supporting members, said gate comprising upper and lower horizontally extending bars connected together, a shiftable locking member carried by the mattress section and cooperating with the lower horizontal bar for releasably supporting the gate, and means carried by a supporting member for operating said locking member.

7. In a crib, the combination of a pair of upright end members having legs adapted to rest upon the floor, a mattress section connected thereto and comprising a pair of 5 U-shaped end frames connected together by a spring fabric, side bars connecting said frames below the mattress fabric, a vertically slidable gate, means carried by an end frame releasably supporting said gate, and 10 means carried by an upright end member for releasing said means.

8. In a crib, the combination of a pair of upright end members having legs adapted to rest upon the floor, a mattress section 15 connected thereto and comprising a pair of U-shaped end frames connected together by a spring fabric, side bars connecting said frames below the mattress fabric, a vertically slidable gate, means for releasably 20 supporting said gate, and means carried by an upright end member for shifting said means to release the same.

9. In a crib, the combination of a pair of upright end members having legs adapted 25 to rest upon the floor, a mattress section connected thereto and comprising a pair of U-shaped end frames connected together by a spring fabric, side bars connecting said frames below the mattress fabric, a vertically 30 slidable gate, cooperating means carried by an end frame and end member for releasably locking the gate and comprising a swinging locking member, and an operating 35 member connected thereto for shifting the same in opposite directions.

10. In a crib, the combination of a pair of upright end members having legs adapted to rest upon the floor, a mattress section connected thereto, a vertically slidable gate, 40 a locking member for releasably supporting the gate, and a pedal operated member carried by an upright end member for swinging 45 said locking member.

11. In a crib, the combination of a pair 45 of upright supporting members having legs resting on the floor, a mattress section extending therebetween, a vertically slidable gate guided by said supporting members, a movable locking device for releasably supporting said gate, and a pedal operated member carried by an upright supporting 50 member for operating said locking device.

12. In a crib, the combination of a pair of upright end members, a mattress section 55 connected thereto, a vertically slidable gate, and means for releasably locking said gate in elevated position, said means comprising a pair of swinging locking members located one at each end of said gate, a lengthwise 60 extending rod rotatably supported and connecting said locking members together, and pedal operated means for rotating said rod to simultaneously shift both locking members.

13. In a crib, the combination of a pair

of upright end members, a mattress section connected thereto, a vertically slidable gate, and means for releasably locking said gate in elevated position, comprising a swinging locking member having a part shiftable 70 into and out of position beneath a part of said gate, pedal operated means for shifting said locking member out of locking position, and resilient means for shifting the locking member into locking position. 75

14. In a crib, the combination of a pair of heads, a mattress section detachably connected thereto, a sliding gate guided by said heads, a locking member carried by the mattress section for releasably supporting said gate, and means carried by one of said heads and releasably connected to said locking member for operating the same. 80

15. In a crib, the combination of upright supporting members, a mattress section connected thereto, a vertically slidable gate guided on said supporting member, a swinging locking member pivoted to said mattress section between one outer end thereof and a supporting member for releasably 85 supporting said gate.

16. In a crib, the combination of a pair of upright end members, a mattress section connected thereto, a vertically slidable gate, means for releasably locking said gate in elevated position, said means comprising a pair of locking members located one at each end of said gate, a rotatable rod connecting said locking members together, and means for rotating said rod to shift said 95 locking members.

17. In a crib, the combination of a pair of heads, a mattress section connected thereto, a sliding gate supported by said heads, means for releasably supporting said gate 105 and comprising a pivoted locking member having a crotched portion, and an operating member for swinging said locking member and having a projecting part extending into said crotch. 110

18. In a crib, the combination of a pair of upright end members having legs adapted to rest upon the floor, a mattress section connected thereto and comprising a pair of U-shaped end frames connected together by a spring fabric, side bars connecting said frames below the mattress fabric, a vertically 115 slidable gate, a shiftable locking member supported above the side bar at one longitudinal side of the crib and shiftable into and out of locking engagement with the lower part of the gate.

19. In a crib, the combination of a bed structure including supporting ends, a vertically slidable gate guided on said bed structure, locking means for releasably locking said gate in elevated position, and spring controlled means for shifting said locking means in opposite directions. 125

20. In a crib, the combination of a pair

of heads, a mattress section connected thereto, a sliding gate supported by said heads, means for releasably supporting said gate and comprising a two-armed locking member pivoted intermediate the ends of the arms, one arm having a part engageable with the gate, and a member operating in-

dependent of said gate and cooperating with the other arm for swinging the locking member.

Signed at Brooklyn, New York, this 17th day of June, 1924.

CONRAD KLEIN.
